CLAIM

The ornamental design for a housing for a telephone, as shown and described.

DESCRIPTION

FIG. 1 is a side elevational view of one side of a housing for a telephone showing my new design, the side opposite being a mirror image thereof;

FIGS. 2 and 3 are respectively front and rear elevational views thereof;

FIGS. 4 and 5 are respectively top and bottom plan views thereof.

FIG. 1.

FIG. 2.

FIG. 3.
